Hot Chillys Chil-Block Half Mask, [on-line]; [first made available to the Internet on Jul. 6, 2017 (see p. 2)]; [retrieved from the Internet on Aug. 14, 2018]; URL: see first page of provided copy. (2 pgs). (Year: 2017).*

Primary Examiner — Karen S Acker*Assistant Examiner* — Jasmine Mlinarcik(74) *Attorney, Agent, or Firm* — Matthew J. Spark;
Stephan J. Kirchanski; Zuber Lawler & Del Duca LLP(57) **CLAIM**

The ornamental design for a face mask, as shown and described.

DESCRIPTION

FIG. 1 is a perspective view of a face mask;
FIG. 2 is a top plan view of the face mask of FIG. 1;
FIG. 3 is a front view of the face mask of FIG. 1;
FIG. 4 is a rear view of the face mask of FIG. 1;
FIG. 5 is a side view of the face mask of FIG. 1; and,
FIG. 6 is another side view of the face mask of FIG. 1. The broken lines illustrating a figure wearing the face mask assists in illustrating how the claimed design may be worn and depict environmental subject matter that forms no part of the claimed design.
